SIGNAL AMPLIFYING SYSTEM AND METHOD

Filed April 30, 1929

UNITED STATES PATENT OFFICE

HOLLIS S. BAIRD, OF BOSTON, MASSACHUSETTS, ASSIGNOR TO SHORTWAVE & TELEVISION CORPORATION, OF BOSTON, MASSACHUSETTS, A CORPORATION OF DELAWARE

SIGNAL AMPLIFYING SYSTEM AND METHOD

Application filed April 30, 1929. Serial No. 359,348.

This invention relates to signal amplifying systems especially adapted to amplify an input signal to a high degree over a wide range of frequencies with a minimum of distortion. The amplifying system is here illustrated in connection with the amplification of television signals although it is not necessarily limited to such use.

For the amplification of television signals especially, an amplifying system is desirable which will amplify the input signal throughout a wide range of frequencies without appreciable distortion, otherwise a distorted image will result. The amplifying system, especially at the transmitter, must also have a very high overall amplification due to the very weak voltage change which is provided by the visual-wave responsive-device, usually a photo-electric cell. An amplifying system capable of fulfilling the above requirements constitutes one of the objects of the present invention.

The usual amplifying system embodies the usual multi-element thermionic tubes connected in cascade, wherein the output or plate circuit of one tube influences the input or grid circuit of the next succeeding tube. A resistance amplifying system involving the use of a plurality of thermionic tubes, wherein resistors are included in the plate or output circuits of the tubes, the variation of voltage across the resistors varying the potential of the grids of the next succeeding tubes is well known and has the property of amplifying the input signal with as little distortion as any amplifying system previously known. However, with this type of amplifier, some means must be provided to maintain the grids of the tubes at a suitable negative potential or bias and to keep the high potential of the plates isolated from the grids. A common method involves the use of a coupling or grid condenser and grid leak which are interposed between the grid and the plate circuit of the last preceding tubes. Such grid condensers and grid leaks are not satisfactory especially for the amplification of television signals because of the distortion of the signal at various frequencies and the hazardous voltage fluctuations that result in

their use, especially with high amplifications, and great tendency to overload with increasing amplification. In a high gain amplifier when not using the coupling condenser one of the biggest sources of distortion is eliminated, the leakage in this condenser arising in each stage and, in the initial stage, may be as great as the signal itself.

One of the objects of the present invention is the provision of an improved amplifying system of this general character wherein the grid of one tube is made responsive to the variation of potential across a resistor in the plate circuit of the last preceding tube and wherein the grid is maintained at a proper biasing potential from the plate power by means of the normal plate current.

A further object of the present invention is the provision of a practical means of obtaining grid bias in a direct coupled amplifier, so that the amplifier may use standard blocks of plate battery and operate over periods of time with a minimum of adjustment.

In carrying out these objects of the invention, I provide a separate source of energy, or plate battery, for the plate circuit of each amplifying stage of the system, which plate battery is divided into two sections connected through a resistor which is variable, at least in part, so that the normal plate current can be varied to permit proper adjustment of the grid bias. The grid circuit of one tube includes the resistor and one section only of the battery, the other battery-section being out of the grid circuit. As thus arranged, each plate circuit has its full high potential and yet due to the drop across the resistor caused by the normal plate current flowing therethrough, the grid can be adjusted to have its normal bias and yet respond to variations of voltage across the resistor.

A further object of the invention is generally to improve signal amplification systems and methods.

The figure is a circuit diagram of a signal amplification system embodying the present invention especially adapted for amplifying the input signals from a photo-electric cell.

The amplifying system here shown con-

sists of five stages *a*, *b*, *c*, *d* and *e*, of which the first four stages *a*, *b*, *c* and *d* each have similar thermionic tubes 10 which have grids 12, anodes or plates 14, and heated cathodes 16. The thermionic tubes of the first four stages are of the shielded grid type having the shields or screens 18 surrounding the plates 14 and interposed between the plates and grids. The apparatus of each stage can be enclosed in a metal casing 20 to prevent electro-magnetic coupling between the stages. The filaments of the stages are heated from a suitable source of power here shown as the battery 22. The signal to be amplified is caused to affect the potential of the grid 12 of the first stage tube. As here shown, the input circuit of the first stage is associated with one or more photo-electric cells 24 provided with a suitable source of potential 26. The grid is maintained at a suitable bias by means of the battery 28 and the variable potentiometer 30 which is connected to the grid through the grid leak 32. The tube 10 of the last stage *e* is or can be a three element tube of the power amplifier type and has its output circuit 33 connected with the load 34.

In accordance with this invention, the anodes of the stages *a*, *b*, *c* and *d* are separately supplied with sources of direct current power, each source of which consists of a battery having two separate sections 38 and 38a respectively, arranged in series in the output circuits of the tubes and connected by an interposed resistor 40 which is variable at least in part. The grid of each tube of an amplifying stage is connected by a conductor 42 to the output circuit of the preceding stage at the junction between the power source or battery 38a and the resistor 40. The cathodes of all the tubes are connected together and the negative side of the anode batteries are connected to the cathodes, as is usual practice. The second grid or screen 18 of each of the tubes of the amplifying stages is maintained at its normal potential from a suitable voltage tap of the power source 38 at the filament or cathode end of the output or plate circuit. As thus arranged, the resistor 40 is common to the output and input circuits of successive amplifying stages so that the grid of one stage is responsive to variations of potential across the resistor of the immediately preceding stage and acts to amplify the signals causing such variations of potential.

The normal current in the output circuit causes a normal difference in potential between the terminals of the resistor. This potential opposes the potential of the power source 38 so far as the effect of said source on the grid connected therewith is concerned and, by varying the value of the effective resistance of and thereby the drop across said resistor, the normal or biasing potential of the grid can be adjusted to the normal value

for which the tube is designed. Thus, while the plates or grids of successive tubes are directly coupled together, and thus the grids are connected to the high tension side of the plate power source, yet the grids can have a proper and lower biasing potential. 70

This arrangement has been found to be highly effective in that signals can be amplified without perceptible distortion from zero up to fifty thousand cycles and with good 75 amplification from fifty thousand up nearly to one hundred thousand cycles without deleterious distortion.

It will be apparent that with this system of amplification, distortion of the amplified signal is due mainly to the presence of stray capacity. With the system here shown such 80 capacities are minimized since the usual grid condenser and grid leak is eliminated and the power sources are located in the plate circuits, where the stray capacity between the batteries and the ground, as the side walls of the enclosing casings 20, is not objectionable due to an easily obtained large spacing 85 between the two. Thus the amplifying system here shown can amplify faithfully over a wide range of frequency and can realize to a higher degree than heretofore a greater part of the high amplification factor provided by the four-element or screened-grid 90 tubes here shown.

The amplifier can be adjusted very easily, it being necessary only to insert a milliammeter in the jacks 44 of the plate circuits 100 of the tubes and adjust the resistors 40 until the normal plate current is the same in all tubes.

I claim:

1. A signal amplifying system comprising successive amplifying stages each having a thermionic amplifying tube with a grid and an anode and an input and an output circuit, with the output circuit of one stage having a portion which is common to the input circuit of the next succeeding stage, the common portions of said circuits including a source of anode power and a resistor therein which is variable at least in part, the potential drop of which affects said input circuit, and said output circuit having a second source of power in a portion thereof between said anode and said resistor which is independent of said input circuit. 105

2. A signal amplifying system including successive stages having thermionic amplifying tubes with input grid circuits and output anode circuits, the output anode circuit of one stage being common in part with the input grid circuit of the next successive stage and having in such common part a source of anode power and in series therewith a device the potential across which is responsive to the normal current in said output circuit and opposes the potential of said power source, whereby the grid of said input circuit 120

is subject to the difference of such potentials, and said output circuit having a second source of anode power in series with said first source and in a part of said output circuit between the anode and said device that is separate from said input circuit.

3. A direct-coupled signal amplifier having successive amplification stages each including a thermionic tube having a heated cathode, a grid, and an anode, the cathode of said tubes having a common source of heating current, the anode of the tube of one stage having an output circuit between it and its cathode which includes in series two sources of anode power and an interposed resistor, the grid of the tube of the next succeeding stage having a direct connection with said output circuit between one of said power sources and said resistor and the circuit of said grid including said resistor and said other power source.

4. A signal amplifier having successive amplifying stages each of which has a thermionic amplifying tube provided with a grid, an anode and a cathode, a common source of power for the cathodes of all tubes, input circuits associated with the grids, and output circuits associated with the anodes, the input circuit of one tube being responsive to conditions in the output circuit of the last preceding tube, a source of power in said output circuit, and means located in said output circuit arranged to maintain the grid of the next succeeding tube at a negative potential which is less than the potential of said power source.

5. A signal amplifier having successive amplifying stages each including a thermionic tube having a grid, a cathode and an anode, input and output circuits associated with said grid and anode respectively, the output circuit of one stage being common in part with the input circuit of the next succeeding stage, a source of anode power in the common portion of said input and output circuits, and means to maintain a biasing potential on the grid associated with said input circuit including a resistor in series with said source of power and both of said circuits, and a second source of potential which is in a part of said output circuit between the anode and said resistor that is independent of said grid circuit.

6. A signal amplifier having successive amplifying stages each including a thermionic tube having a grid, a cathode and an anode, input and output circuits associated with said grid and anode respectively, the output circuit of one stage being common in part with the input circuit of the next succeeding stage, a source of anode power in the common portion of said input and output circuits, and means to maintain a biasing potential on the grid associated with said input circuit including a resistor in series with said

source of power and in both of said circuits, and a second source of potential which is in a part of said output circuit between the anode and said resistor that is independent of said grid circuit, said resistor being variable at least in part whereby to vary the biasing potential of the grid.

7. In a resistance coupled amplifier, a three element thermionic tube having a cathode, a grid, and an anode, an output circuit including said cathode and anode, two sources of anode power and an interposed resistor connected in series with said cathode and anode, and a second three element thermionic tube having a grid, a cathode, and an anode, and a grid circuit which includes said grid and cathode and said resistor and one of said power sources only of said output circuit, said other source of anode power being in said output circuit between the anode and said resistor, and a common source of heating current for the cathodes of both tubes.

8. In a resistance coupled amplifier, a three element thermionic tube having a cathode, a grid, and an anode, an output circuit including said cathode and anode, two sources of anode power and an interposed resistor connected in series with said cathode and anode, and a second three element thermionic tube having a grid, a cathode, and an anode, and a grid circuit which includes said grid and cathode and said resistor and one of said power sources only of said output circuit, the other source of anode power being connected between the anode and said resistor, and the cathodes of both tubes having a common connection with a source of power, the potential of said power source that is in said grid circuit and the normal potential drop across said resistor providing a suitable grid-biasing potential.

9. A signal amplifying system including successive amplifying stages having thermionic amplifying tubes and grid and anode circuits, the anode circuit of one stage being common in part with the grid circuit of the next succeeding stage, an anode source of power and a resistor in said common part of said circuits, said resistor having such a value of resistance that the potential across it due to the normal anode current traversing it is greater than and opposes the potential of said power source, whereby to subject the grid to a suitable negative biasing potential, and a second source of anode power in a portion of said anode circuit between the anode and said resistor that is independent of said grid current.

10. A high gain amplifier including two cascaded thermionic tubes the first of which has a shielded grid, the output circuit of the shielded grid tube being common to part with the input circuit of the second tube, a resistor and a source of plate power in such common parts of said circuits, said shielded

grid having a potential connection with said source of power, and a second source of plate power in a part of said output circuit between the plate and said resistor that is independent of said input circuit.

In testimony whereof, I have signed my name to this specification.
